UNITED STATES PATENT OFFICE.

GEORGE F. RICHARDSON, OF MARTINSVILLE, INDIANA, ASSIGNOR TO EDWIN L. BROWN, OF SAME PLACE.

DESIGN FOR A CHAIR.

SPECIFICATION forming part of Design No. 24,388, dated June 11, 1895.

Application filed May 13, 1895. Serial No. 549,191. Term of patent 3½ years.

To all whom it may concern:

Be it known that I, GEORGE F. RICHARDSON, a citizen of the United States, residing at Martinsville, in the county of Morgan and State of Indiana, have invented and produced a new and useful Design for Chairs; and I do hereby declare the following to be a full, clear, and exact description of the invention, such as will enable others skilled in the art to which it applies to make and use the same.

The leading features of my design are in those parts which are above the seat portion of the chair. The two front legs A, A, extend vertically from the floor to their intersection with the seat and from thence are bent outwardly. The back legs or posts B, B, starting from the floor are carried approximately in a vertical direction until they meet the seat and are thence curved outwardly and finally make a return bend and extend a short distance in an approximately vertical direction. Bent cross bars C, C, connect the upper ends of the posts B, B, and have their ends overlapping said posts. The distance apart of the bars is about equal to the distance apart of the posts. The four sided frame thus

formed is filled in with the woven splint strands E in the pattern shown in the drawing. The bent bars F and F' are of horse shoe shape and reach from the inside of one of the posts A to the inside of the other of the said posts and are in contact with the posts B, B. The curvature of the upper bar is larger in diameter than the lower one. The space between the two bars with the exception of a few inches adjacent to the posts A, is filled in with woven splint work. The bottom G is also of woven splint work.

All of the posts, bars, and rounds, are covered with the natural bark of the second growth hickory.

The same design can be used for chairs with or without rockers.

What I claim is—

The design for a chair, substantially as shown and described.

In testimony whereof I affix my signature in presence of two witnesses.

GEO. F. RICHARDSON.
